United States Patent Office.

HENRY BUDD AND SAMUEL W. BUDD, OF PHILADELPHIA, PENNSYLVANIA.

Letters Patent No. 86,641, dated February 9, 1869.

IMPROVEMENT IN LATCHES.

The Schedule referred to in these Letters Patent and making part of the same.

To all whom it may concern:

Be it known that we, HENRY BUDD and SAMUEL W. BUDD, of the city and county of Philadelphia, and State of Pennsylvania, have invented a new and useful Improvement in Dead-Latches; and we do hereby declare that the following is a full and exact description thereof, reference being had to the accompanying drawings, and to the letters of reference marked thereon.

The object of our invention is the construction of a cheap latch, that possesses all the requisite properties of a more costly one.

For the accomplishment of this end, we make the bolt and ratchet-stop in a single piece. We also dispense with the ordinary spring connected with the ratchet, by the peculiar construction and arrangement of a spring in relation to the combined bolt and ratchet-stop, so that it is made to have a longitudinal bearing upon the bolt and a lateral bearing upon the ratchet, holding the latter either right or left, as may be required, in either position into which it is brought.

The construction and operation of the improved latch are fully explained in the following description.

In the accompanying drawings, which make a part of this specification—

Figure 1 is a plan of the latch with the cap-plate D removed.

Figure 2 is an edge view of the combined bolt B and ratchet-stop C.

Figure 3 is a face view of the cap-plate D.

Figure 4 is a perspective view of the spring E.

Like letters in all the figures indicate the same parts.

A is the case;

B is the bolt; and

C, the ratchet-stop.

Instead of the latter being pivoted to the former, as in the ordinary construction, we cast the two in one piece, thereby simplifying the construction, whereby the cost of the latch is reduced, besides making it less liable to get out of order.

The combined bolt and latch is shown in detail in figs. 1 and 2.

D is the cap-plate, which is shown detached in fig. 3.

E is a wire spring, which is shown detached in fig. 4.

The tube-part of the spring fits on the stud F of the face-plate a of the case A, and when the spring is sprung into its place, the end, 1, bears against the contiguous end of the case A.

The end, 2, of the spring has a double incline, which bears against the double inclines of the lug b, on the bolt B.

When the ratchet-stop C has not a fixed connection with the case A, the incline, 3, of the lug b, as seen in fig. 1, when the combined bolt and ratchet is in the position represented by black lines, whereby the straight edge of the ratchet is borne against the contiguous edge of the cross-groove c, of the end of the case A; but when the ratchet is brought into a fixed connection with the case, as represented by red lines, the incline, 5, of the spring, is brought to bear against the incline, 6, of the lug b, so as to hold the catch in its fixed position until it is changed by hand.

In all the positions of the bolt, the spring, as will be observed, has a forward pressure, as well as a lateral one, and performs the double function of a bolt and a ratchet-spring.

Having thus described our invention,

What we claim as new, and desire to secure by Letters Patent, is—

The combination and arrangement of the spring E with the case A and combined bolt and ratchet-stop B C, substantially as described, and for the purposes specified.

In testimony that the above is our invention, we have hereunto set our hands and affixed our seals, this 8th day of August, 1868.

HENRY BUDD. [L. S.]
SAMUEL W. BUDD. [L. S.]
